US00D658288S

(12) **United States Design Patent**
Ryshkus et al.

(10) **Patent No.:** **US D658,288 S**
(45) **Date of Patent:** **** Apr. 24, 2012**

(54) **ANTERIOR RETRACTOR**

(75) Inventors: **Chad Ryshkus**, Kansasville, WI (US);
Jonathan P. Crandall, Fort Wayne, IN (US); **Douglas J. Roger**, Rancho Mirage, CA (US)

(73) Assignee: **Greatbatch Ltd.**, Clarence, NY (US)

(**) Term: **14 Years**

(21) Appl. No.: **29/398,361**

(22) Filed: **Jul. 29, 2011**

(51) **LOC (9) Cl.** **24-02**

(52) **U.S. Cl.** **D24/135**

(58) **Field of Classification Search** D24/133, D24/135, 140; 606/191; 600/201, 210
See application file for complete search history.
